UNITED STATES PATENT OFFICE.

MARSHAL T. REEVES AND JOHN N. KAILOR, OF COLUMBUS, INDIANA,
ASSIGNORS TO REEVES & CO., OF SAME PLACE.

DESIGN FOR A SEPARATOR OR CLOVER-HULLER TOOTH.

SPECIFICATION forming part of Design No. 28,894, dated June 21, 1898.

Application filed February 28, 1898. Serial No. 672,106. Term of patent 14 years.

To all whom it may concern:

Be it known that we, MARSHAL T. REEVES and JOHN N. KAILOR, citizens of the United States, residing at Columbus, in the county of Bartholomew and State of Indiana, have invented and produced a new and original Design for Separator or Clover-Huller Teeth, of which the following is a specification.

The accompanying drawings illustrate our design for separator or clover-huller teeth.

Figure 1 is a perspective view of a separator-tooth embodying our design. Fig. 2 is a section through the base. Fig. 3 is a rear end view.

The tooth is provided with a shank 2. Between the upper portion 1 of the tooth and the

shank is the essential feature of our design, the same consisting of a truncated pyramidal portion 3, the smaller end of which is next the shank 2, and a pyramidal shoulder 4, formed upon one of the faces of the portion 3, the base of said shoulder joining the lower end of the upper portion 1 of the tooth. 20

We claim as our invention and production— 25

The design for a separator or clover-huller tooth, substantially as shown and described.

MARSHAL T. REEVES.
JOHN N. KAILOR.
